(57) **CLAIM**

The ornamental design for a bottle, as shown and described.

DESCRIPTION

FIG. 1 is a front perspective view of our bottle;

FIG. 2 is an elevation view of the front thereof;

FIG. 3 is an elevation view of the rear thereof;

FIG. 4 is an elevation view of the right side thereof;

FIG. 5 is an elevation view of the left side thereof;

FIG. 6 is a plan view of the top thereof; and,

FIG. 7 is a plan view of the bottom thereof.

The broken lines shown in the drawings are included for illustrative purposes only and form no part of the claimed design.
